UNITED STATES PATENT OFFICE.

EDWARD L. MEGILL, OF BROOKLYN, NEW YORK.

FEED-GAGE FOR PRINTING-PRESSES.

SPECIFICATION forming part of Letters Patent No. 703,734, dated July 1, 1902.

Application filed April 12, 1902. Serial No. 102,504. (No model.)

To all whom it may concern:

Be it known that I, EDWARD L. MEGILL, a citizen of the United States, residing in the city of New York, borough of Brooklyn, county of 5 Kings, and State of New York, have invented certain new and useful Improvements in Feed-Gages for Printing-Presses, of which the following is a specification.

This invention relates to improvements in 10 platen-printing-press feed-gages which are formed from thin sheet metal and in which the part known as the "gage-head" presents an approximately high surface or wall with wings bent to the rearward.

15 The object of this invention is to form a brace for these wings and to shield the hand from injury against them, they being somewhat sharp.

In the accompanying drawings, Figure 1 is 20 a perspective view of the feed-gage complete with a sliding tongue, the same being mounted in position on a fragment of the tympan, with a fragment of a card fed to the gage-head. Fig. 2 is a top plan view of two of the 25 feed-gages as set in position on the tympan for printing with a full-size card fed to them.

A is the tympan-sheet ordinarily employed on the platen of a press, and B is the card fed to the feed-gage.

30 Of the feed-gage, 1 is the prong which holds the feed-gage in position on the tympan. 2 represents arms or shanks which extend rearwardly from the upper part of the gage-head 4 and partially support it as against the pressure of the sheet in feeding. These shanks 35 2 also form guideways for the sliding tongue 3. 5 represents the wings of the gage-head, which are bent to the rearward to round off the corners and facilitate the movement of 40 the sheet in feeding. All these are parts commonly employed in a feed-gage, the shanks 2, however, sometimes being reduced to a single shank and used as the part by which the gage-head is secured by the aid of other means 45 than a prong to the tympan or platen.

Attention is now called to the guards 6, which extend laterally from the shanks 2 immediately back of the wings 5 and which abut against them at their rear. These guards 6 brace the said wings 5 and serve to shield 50 them.

To further explain the object of the guards 6, it is well to state that in feeding small sheets or cards the hand is run down between the two bottom feed-gages to get hold of and 55 withdraw the said sheets or cards from the tympan, and in doing so the hand is brought in contact with the side of the gage-head, the gage either becoming displaced thereby or the hand cut, or both, in the absence of the 60 guards.

Any feed-gage for the platen formed from sheet metal having an approximately high gage-head 4 and wings 5, joined to a rearwardly-projected supporting-shank or arms 2, 65 similar to those shown herein, may embody this improvement.

Having thus described my invention, I claim—

1. A feed-gage for platen printing-presses 70 formed of thin sheet metal, having a gage-head with rearwardly-bent wings, and laterally-projecting guards in their rear, whereby the said wings are shielded and braced, substantially as set forth. 75

2. In a feed-gage for platen printing-presses formed from thin sheet metal, a gage-head having rearwardly-bent wings, and a rearwardly-extended supporting-shank, said shank being provided with lateral guards, whereby the said 80 wings are braced and shielded, substantially as set forth.

Signed at New York, in the county of New York and State of New York, this 11th day of April, A. D. 1902.

EDWARD L. MEGILL.
